UNITED STATES PATENT OFFICE.

ALBERT M. JOHNSON, OF CLEVELAND, OHIO.

ELECTRIC RAILWAY-SWITCH SIGNALING DEVICE.

1,189,116.

Specification of Letters Patent. Patented June 27, 1916.

Application filed June 1, 1914. Serial No. 842,287.

To all whom it may concern:

Be it known that I, ALBERT M. JOHNSON, a citizen of the United States, residing at Cleveland, in the county of Cuyahoga and State of Ohio, have invented a new and useful Electric Railway-Switch Signaling Device, of which the following is a specification.

My invention relates to improvements in electric railway-switch signals and is operated by attaching the said device to the switch blade of a steam or electric railroad near the point thereof and connecting the said device by electric wires on one hand to the red and white lights of the electric switch signal and on the other to the feed wire for electric current.

The object of my improvement is to provide a device which can be attached to any railway switch blade near the point thereof, and which is further attached with electric wires with the red and white lights of an electric switch signal on the one hand, and with the feed wire for electric current on the other, so that when the switch blade is moved to and fro by opening and closing the switch, said device automatically makes contact and thereby produces a red or white light in the switch signal.

I attain these objects by the mechanism illustrated in the accompanying drawing.

Figure 1 is a perspective view of the entire device. Fig. 2 is a view of the railway track of a steam or electric road showing how the electric signaling device may be attached, when in use, to the railroad tie and to the switch blade, and also showing the position of wires running to switch signal lights and the feed wire for current.

A. is the sliding arm with a nut to fasten it to the switch blade which arm is insulated from the contact blade.

B. is the sliding contact blade.

C. is a contact prong for the white light of the switch signal. D. is the contact prong for the ground wire or neutral wire and is neutral to C or E. E. is a contact prong for the red light of the switch signal. F. is the insulated base which said contact prongs C, D and E are mounted on and insulates these contact prongs from the cast iron box H.

G. is the insulator which insulates the contact blade B from the sliding arm A.

H. is a cast iron box which supports the switch signaling device and also protects it from the weather and other damages that might happen to it. I. is the cast iron cover to said box H.

J. is an electric wire which runs to the red light of the switch signal which may be located at the switch or anywhere desired.

K. is the neutral wire for both red and white lights.

L. is an electric wire which runs to the white light of the switch signal.

When the switch blade is moved in opening or closing the switch, the sliding arm A attached to said switch blade likewise is moved and thereby automatically changes contact producing a red or white light as the case may be.

I claim for my invention:

In a circuit changing switch, a carrying bar of polygonal cross section, polygonal 75 bearings journaling said bar to limit the latter to linear movement and prevent rotary movement of said bar, means for moving said bar to and fro to predetermined positions, a flat straight switch blade having 80 one side edge rigidly secured to said bar, a plurality of aligned spring terminal contact clips for electrical engagement with the remaining margin of said blade on opposite sides thereof, and having their longitudinal 85 axes at right angles to the direction of movement of the blade, one of said clips being in constant sliding engagement with a central portion of said blade, the remaining or end terminals being spaced apart from 90 the central terminal sufficiently with respect to the length of said switch blade to cause the latter to close circuit between said central and the end terminal toward which the blade is moved endwise in one position, and 95 open circuit with respect to the remaining or other end terminal, and vice versa, substantially as described.

ALBERT M. JOHNSON.
